R. F. R. HUNTSMAN.
DEVICE FOR MAKING SMOKE RINGS.
APPLICATION FILED JAN. 10, 1913.

1,103,514.

Patented July 14, 1914.

THE NORRIS PETERS CO., WASHINGTON, D. C.

UNITED STATES PATENT OFFICE.

ROBERT F. R. HUNTSMAN, OF PLAINFIELD, NEW JERSEY.

DEVICE FOR MAKING SMOKE RINGS.

1,103,514.

Specification of Letters Patent.

Patented July 14, 1914.

Application filed January 10, 1913. Serial No. 741,364.

To all whom it may concern:

Be it known that I, ROBERT F. R. HUNTSMAN, a citizen of the United States, and a resident of Plainfield, county of Union, 5 and State of New Jersey, have invented a certain new and useful Device for Making Smoke Rings, of which the following is a specification.

One of the objects of the invention is to 10 provide an envelop, preferably a box which may be used as a holder for cigars or cigarettes, and which when empty may be used as a device or toy for making smoke rings.

Other objects will appear from the here- 15 inafter description.

Certain embodiments of the invention are illustrated in the accompanying drawings which form a part of this specification, and in which the same reference character in- 20 dicates the same part in the several views.

Referring to the drawings, Figure 1 is a perspective view of a box formed of an open end structure covered by a sliding drop or container fitting in the same; Fig. 2 is a 25 cross-sectional view of the same, showing the box used as a receptacle for cigars or cigarettes; Fig. 3 is a cross-sectional view showing the box as used for a smoke-making device; Fig. 4 is a cross-sectional view of a 30 modified form of the same; Fig. 5 is a cross-sectional view of another modification; Fig. 6 is a perspective view of an embodiment of a simpler form of construction of the invention; and Fig. 7 is a cross-sectional view 35 of Fig. 6.

The part marked A on the drawings represents the outside or cover of the box, preferably rectangular in form and open at both ends, 20 and 21, to receive the sliding holder 40 or container, B, within which cigars or cigarettes, C, may be carried. The container B is preferably made of a single piece of material, cut and folded to form part of the front, 30, one end 31, the back 32, the other 45 end 33, front flap 34, and the two sides. The part marked 30 and the flap 34 form the front of the sliding container, and their meeting edges are about half way longitudinally of the box. The edges 37 and 38 of 50 this container are scored or creased, so that when the container is partly withdrawn from the cover A, the flap 34 may be easily turned up to remove the contents of the container.

55 On the front 22 of the cover is a repre-

sentation, 24, of the face of an individual, the mouth 25 of which is shown open. The front 22 of this cover is provided with an opening, 26, which registers with the open-mouth of the front face of the cover. The 60 front part 30 of the slideable container is perforated at 39, and it is so located that when the sliding container is within the cover, said perforation is out of register with the opening 26 in the front of the cover, as 65 shown in Fig. 2 of the drawings; but when the said container is partly withdrawn, the said perforation 39 corresponds with and registers with the opening 26 in the cover of the box.

The object of placing the opening 39 out of register with the opening 26 in the box as used as a receptacle for cigars, is to prevent the cigars from becoming dry; but when the cover is partly withdrawn, the 75 openings register as shown in Fig. 3, so that it may be used for projecting smoke rings.

In Fig. 4 I have shown a construction in which the openings register when the sliding container is pushed in to its fullest extent in the cover. In this case I may provide the upper edge of the part 30 with a flap 40, which folds over the opening 39, and covers the same, so that the moisture in the cigars or cigarettes will not evaporate and 85 cause the said cigars or cigarettes to become dry.

In some cases, where the openings 26 and 39 register when the slide is in the cover, one of said openings may be covered by a thin 90 piece of paper, 50. I have shown the opening 39 as so covered in Fig. 5 of the drawing.

In Figs. 6 and 7 I have shown a simpler construction, which consists of the box B 95 and the cover B', said cover being provided with an opening 70, covered by a piece of paper 71. The front of this cover has the representation of a face thereon, as in the preceding described construction. In some 100 cases, instead of providing the opening in the cover or the receptacle, and covering the same with a piece of paper, I may make the outline of the opening or openings formed by marking or scoring through the cover or 105 the slide, and the opening may be made by cutting or punching out the indicated part when the box is embodied to use it as a smoke-making and projecting device.

To use the receptacle shown in Figs. 1 to 110

3 inclusive, as a smoke-making and projecting device, the empty receptacle is partly withdrawn from the cover, so that the openings 26 and 39 will register. Then the 5 smoke from a cigar is blown into the receptacle through these registering openings, then by tapping the box gently on the back the rings will be formed and projected as shown in Fig. 3.

10 When the construction shown in Fig. 4 is used, the flap 40 is simply raised to uncover the opening when the smoke is blown into the box, and is tapped on the back to produce the rings.

15 In the other figures, the piece of paper 50 or 71 is torn from the opening, or the scored part punched out, when the smoke can be blown into the holder and projected in rings by tapping on the back. The box or 20 receptacle is preferably made of cardboard or heavy paper, although any suitable material may be used; but whatever material is used, it is preferable, though not necessary, that the back of the box be slightly 25 flexible; and when I have used the term box or receptacle, it is intended any suitable box, or even a paper bag itself may be used for this purpose.

It is also to be understood, that the area 30 of the opening is preferably considerably less than the area of the front of the box.

In addition to the invention being described as herein set forth, as a receptacle for cigars, and when empty to be used as a 35 toy for making smoke rings, it is apparent that it may be used as an advertising scheme.

Having now described my invention, what I claim as new and desire to secure by Letters Patent is:

1. A device of the class described, comprising an open end cover, having an opening in the front thereof and a container 45 slideable in said cover, the front of the container also having an opening normally out

of register with the opening in the front of the cover.

2. A device of the class described, comprising an open end cover, having an opening in the front thereof, a container slideable 50 in said cover, the front of said container provided with an opening to register with the opening in the cover, and removable means for closing one of said openings.

3. A device of the class described comprising an open end cover having a representation of a face on the front thereof, the mouth of said face being represented as open, an opening in the front of the cover registering with the mouth of the face, and 60 a container slidably mounted in said cover, the front of said container provided with an opening to register with the opening in the cover.

4. A device of the class described comprising an open end cover having a representation of a face on the front thereof, the mouth of said face being represented as open, an opening in the front of the cover registering with the mouth of the face, a 70 container slidably mounted in said cover, the front of said container provided with an opening to register with the opening in the cover, and removable means for covering one of said openings.

5. A device of the class described comprising a closed box having a representation of a face on the front thereof, the mouth of the face being represented as open, an opening in the front of the cover of the box 80 registering with the mouth of the face, and removable means for covering said opening.

In witness whereof I have hereunto set my hand at the borough of Manhattan, city and State of New York, this seventh day of 85 November, 1912.

ROBERT F. R. HUNTSMAN.

In presence of—

JOHN J. RANAGAN,

A. C. O'CONNELL.
